ARCHER'S BOW

Yngve J. Nyvall, San Pedro, Calif.

Application May 9, 1932, Serial No. 610,006

12 Claims. (Cl. 273—107.5)

This invention relates to archers' bows and more particularly pertains to longbows of the collapsible type.

An object of the invention is to provide an archer's bow which is adapted to be folded for convenience in carrying, when not in use, and which embodies an intermediate section on which end members of the bow are carried including hinged joints on which the bow end members may be swung toward and away from each other.

Another object is to provide a construction in the intermediate section whereby the latter may be readily disposed to securely retain the bow end members in their extended bow forming position, and be easily operated to effect folding of the bow.

Another object is to provide a means for varying the tension of the bow, and which is incorporated in the folding section.

Another object is to provide a construction in the bow whereby an arrow may be directed centrally through the bow, including a means whereby the arrow may be inserted laterally into an opening intermediate the ends of the bow.

Another object is to provide a means for facilitating sighting of the arrow and which in conjunction with directing the arrow centrally through the bow will enable shooting the arrow with great accuracy.

A further object is to provide a means in association with the folding features of the bow whereby the bow string may be readily relieved of tension to permit collapsing of the bow and also be placed under tension on assembling the bow.

With the foregoing objects in view together with such other objects and advantages as may subsequently appear, the invention resides in the parts and in the combination, construction and arrangement of parts hereinafter described and claimed and illustrated by way of example in the accompanying drawings, in which:

Fig. 1 is a view of the bow as seen in side elevation in its assembled position;

Fig. 2 is a view of the bow as seen in its collapsed or folded position;

Fig. 3 is a perspective view depicting the intermediate bow section;

Fig. 4 is a detail in horizontal section and plan as seen on the line 4—4 of Fig. 3;

Fig. 5 is a view in vertical section taken on the line 5—5 of Fig. 4;

Fig. 6 is a detail in side elevation as seen in

the direction of the arrow 6 of Fig. 3 with parts shown in section;

Fig. 7 is a view in side elevation of the bow string tensioning and slackening device illustrating the mode of operation thereof;

Fig. 8 is a detail in cross section taken on the line 8—8 of Fig. 7;

Fig. 9 is a view in cross section as seen on the line 9—9 of Fig. 7;

Fig. 10 is a view in cross section as seen on the line 10—10 of Fig. 7.

Referring to the drawings more specifically, A indicates generally the bow which, in carrying out the invention, embodies a pair of complementary bow end members 11 and 12 connected together by an intermediate section B, and a bow string C connected at its ends to the outer end portion of the bow end members.

The members 11 and 12 are formed of curved lengths of suitable flexible material preferably consisting of wood, as is common in archer's bow construction, the inner ends of which are rectangular in cross section and are fitted with U-shaped straps 11' and 12' which extend over the ends of the members 11 and 12 and along opposed sides thereof which straps are held in place by tightly fitting metallic sleeves 14 and 15 which encompass the members 11 and 12 and engage the outer ends of said straps to retain the latter in place.

The intermediate section B embodies a metallic side plate 16 and on which is affixed a pair of spaced sockets 17 and 18 adapted to receive the inner terminals of the bow members 11 and 12; the sockets projecting from the back of the side plate and having their bow end receiving recesses opening oppositely in relation to each other in the direction of the length of the side member 16 and arranged so that when the inner ends of the bow members 11 and 12 are seated therein the outer end portions of the side plate 16 will extend along and abut against one side of the bow member extending between the straps 11' and 12'.

Carried by the sockets 17 and 18 and extending parallel with the side plate 16 are plates 19 and 20 arranged to abut against the bow members 11 and 12 on the side thereof opposite the side plate 16; the inner end portions of the plates 19 and 20 extending through the sockets 17 and 18 and terminating in spaced relation to each other, as indicated at a and b in Fig. 3, to form a slot or space therebetween.

The inner ends of the bow members 11 and 12 when seated in the sockets 17 and 18 between 55

the plate 16 and the plates 19 and 20 will be spaced apart the extent of the spacing of the sockets 17 and 18 thus providing an opening D leading through the bow mediate the ends thereof.

5 The space between the margins *a* and *b* of the plates 19 and 20 serves as a means for permitting introduction of an arrow laterally into the opening D. This space, however, is normally closed by a filler block 21 affixed to a weak plate spring 10 22 attached at one end to the socket 17 as by rivets 23; the spring 22 projecting beyond the block 21 and having its free end curved outwardly over the plate 21 to permit the arrow being readily introduced under the end of the spring 15 so that on shoving the arrow upwardly beneath the spring the latter will be sprung outwardly to withdraw the block 21 from between the ends of the plates 19 and 20 and thereby allow passing of the arrow laterally between the ends *a* and *b* 20 of the plates 19 and 20 into the opening D. As a means for detaining the block 21 in engagement with the ends *a* and *b*, the margins of the latter are of convex or V-shaped cross section and the adjacent margins of the block 21 are concave to 25 conform thereto; the plate 22 being sufficiently resilient to permit it being sprung to such extent as to allow the block 21 to be moved in and out of engagement with the plates 19 and 20.

Projecting inwardly from the margin *b* of the 30 plate 20 and from the inner face of the plate 16 are ledges 25 and 26 which ledges are disposed on a common plane and have their adjacent edges spaced apart to form a slot 27 therebetween, the margins of which slot extend equi-distant on 35 opposite sides of the vertical center of the opening D between the plates 16 and 19—20 with the margins of the slot converging from the rear end thereof toward the forward end thereof. The ledges 25 and 26 afford a support at their forward 40 end portions for the arrow, and the slot 27 serves as a passage and guide for the arrow feathers or vanes.

As a means for affording a combined pivotal and 45 slideable connection between the bow members 11 and 12 and the intermediate section B, pivot pins 30 and 31 are mounted on the bow members 11 and 12 adjacent the inner ends thereof, the outer ends of which extend through elongated slots 32 and 33 formed in the plate 16 and extending longitudinally thereof, as indicated in 50 dotted lines in Fig. 5, and through corresponding slots 34 and 35 formed on the plates 19 and 20, as shown in Fig. 3. The outer ends of the pins 30 and 31 are threaded to receive thumb nuts 36 55 and 37 whereby the bow members 11 and 12 may be tightly clamped between the plates 19 and 20 and the plate 16.

Extending on opposite sides of the inner end 60 portion of the bow member 11 are stiff bowed plate springs 38 and 39 the outer ends of which bear against opposite side members of the strap 11' and which springs extend longitudinally between the plates 16 and 19 and have their inner ends connected together across the inner end of 65 the bow member 11 by a connecting member 40 adapted to seat in the socket 17, and corresponding stiff bowed plate springs 41 and 42 are arranged to bear on opposite side members of the strap 12' on the bow member 12, which springs 70 are connected together by connecting member 43 extending over the inner end of the bow member 12 and adapted to seat in the socket 18; the springs 41 and 42 extending longitudinally between the plates 16 and 20. The outer ends of 75 the springs 39 and 42 are free to slide on the

straps 11' and 12' while the outer ends of the springs 38 and 41 are engaged by tongues 44 and 45 struck from the straps 11' and 12', as shown in Fig. 5. The springs 39 and 42 being arranged on the inner side of the bow act as compression springs, while the springs 38 and 41 being disposed on the outer side of the bow and being attached thereto at their ends act as pull springs, so that both sets of springs serve to yieldably oppose inward flexing of the bow.

10 Formed on the longitudinal margins of the plate 16 are outwardly extending parallel flanges 45' and corresponding marginal flanges 46 and 47 are formed respectively on the longitudinal edges of the plates 19 and 20. The flanges 45 and 46 are adapted to be engaged by slides 48 and 49 carried by the springs 38 and 39, and the flanges 45 and 47 are adapted to be engaged by slides 50 and 51 carried by the springs 41 and 42, the slides extending over the springs and having 20 inturned ends arranged to slidably engage the flanges. Each of the springs 38, 39, 41 and 42 is formed with a longitudinally extending slot 52 and extending through each of the slides 48, 49, 50 and 51 is a headed screw 53 the shank of which 25 extends through the slot 52 and the head 54 of which engages the inner side of the spring on opposite sides of the slot 52. A thumb nut 55 is screwed on the outer end of the screw 53 against the slide whereby the latter may be clamped into 30 engagement with the spring. The slides may thus be adjusted to various positions longitudinally of the springs so as to vary the tension of the end portions thereof projecting from the slides to thereby offer more or less resistance 35 to flexing of the bow members on drawing the string C as will be later described; the inner ends of the bow members being capable of slight flexing movement in a direction such as to be opposed by the springs.

40 The bow-string C is attached at one end thereof to the outer end of the bow member 11 in a usual manner, but as a means for enabling ready assembling and collapsing of the bow the other end of the string is attached to the outer end of the bow member 12 by means of an adjustable connector E adapted to be operated to stretch the string when assembling the bow and to slacken the string when it is desired to collapse and fold the bow.

45 The string connector E is here shown as comprising a sleeve 56 slidably mounted on the outer end portion of the bow member 12 to which the string C is attached by forming the latter with a loop 57 which is engaged with a ring 58 carried on the sleeve 56. A lever 59 is connected at one end thereof to lugs 60 on the sleeve 56 by a pivot pin 61, which lever extends in the direction of the length of the bow member 12 along the outer side thereof and toward the inner end 60 of the bow member. A link 62 is pivotally connected at one end thereof to the lever 59 intermediate the ends of the latter by a pivot 63, the other end of which link is pivoted at 64 to lugs 65 on a collar 66 fixed on the bow member 12 at a point spaced inwardly from the outer end of the latter. The lever 59 is designed to be positioned to extend along the outer side of the bow member 12 and when so arranged the sleeve 56 will be disposed in its outermost string stretching position, as shown in full lines in Fig. 7. The pivot 63 is arranged to then be positioned in inward offset relation to a plane extending through the axes of the pivots 61 and 64 whereby the tension or pull of the string C on the sleeve 56 will

act to thrust the lever 59 and the link 62 inwardly against the bow and thereby automatically hold the sleeve 56 in its outermost position. When it is desired to slacken the string, the lever 59 is pulled outwardly to move the pivot 63 to the opposite side of the plane of the axes of the pivots 61 and 64 thus swinging the link 62 outwardly and sliding the sleeve 56 inwardly along the bow member 12 to a position as indicated in broken lines in Fig. 7. The tension of the bow pulling on the string C will serve to assist in effecting inward movement of the sleeve 56 on the lever 59 and link 62 being slightly swung outward.

The bow is equipped with a sighting device 151 which is here shown as embodying a pair of mirrors F and G which are fixed on the ends of a rock shaft 66 turnably carried in bearings on the side plate 19 and frictionally held against free turning movement. The shaft 66 extends transversely of the bow section B at one side of the bow close to the opening D, and the mirrors are attached to the opposite ends of the shaft by projections 67 and 68 extending from corners of the mirrors whereby the latter may be disposed to project from one side of the bow in a sighting position or turned to a position to overlie the inner and outer faces of the bow section B when not in use. The mirrors extend in offset but parallel relation to each other and are disposed face to face at an angle to the axis of the shaft 66 so that when disposed in their sighting position, as shown in Fig. 6, the mirror F will be disposed with its center on a plane below the lower margin of the mirror G.

35 The mirrors when disposed in their sighting position serve to reflect the target or object to be aimed at, the image of which is reflected by the mirror G onto the lower mirror F and thence to the eye of the archer, as indicated by the broken line H in Fig. 6. The mirror F is reticulated or lined, as indicated at 69 in Fig. 3, in such relation to the longitudinal center of an arrow seating on the arrow supporting ledges 25 and 26, that when the object aimed at appears in the mirror F with the point aimed at appearing at the intersection of central crossed lines of the reticule the arrow will be directed toward such point. However, in aiming, allowance is made for trajectory and currents of air.

40 As a means for facilitating centering of the arrow on the bow string C, the latter has a button 70 fixed thereon in such proximity to the longitudinal center of the string that when the inner end of the arrow is engaged with the string and abutted against the button, with the arrow seated on the ledges 25 and 26, the axis of the arrow will lie on a plane extending centrally of the bow.

When the bow is in its folded or collapsed position the bow members 11 and 12 are disposed to extend substantially at right angles from the intermediate section B to project in corresponding directions therefrom, as shown in Fig. 2, and when so disposed the pivot pins 30 and 31 are arranged adjacent the outer ends of the slots 34 and 35 with the nuts 36 and 37 screwed sufficiently tight on the pins to clamp the bow end members 11 and 12 against free swinging movement relative to the intermediate section. The outer ends of the bow members 11 and 12 will then be disposed contiguous each other thus imparting to the folded structure the general shape of a quiver.

When it is desired to assemble the bow into its operative position, the nuts 36 and 37 are loosened and the bow members 11 and 12 swung outwardly

5 into their extended position with the string connector E in its string slackening position. The inner end of the bow members are then inserted in the sockets 17 and 18, thereby positioning the pins 30 and 31 adjacent the inner ends of the slots 34 and 35 whereupon the nuts 36 and 37 are tightened to securely clamp the bow members relative to the intermediate section B.

The string connector E is then operated by swinging the lever 59 inwardly to effect stretching 10 of the string C and tensioning of the bow 11, as before described.

When it is desired to vary the tension of the bow, that is, to render it stiffer or more flexible, the slides 48, 49, 50 and 51 are adjusted longitudinally of the springs 38, 39, 41 and 42, respectively, to increase or decrease the length of the effective working end portions of the springs, as before described.

In shooting an arrow, the latter is placed to 20 extend through the opening D by inserting it through the slot formed between the margins a and b of the side plates 19 and 20, as before stated, so that the shank of the arrow will then rest upon the ledges 25 and 26. The feathered 25 end of the arrow is then engaged with the string C adjacent the button 70 and the bow drawn and released to effect propulsion of the arrow through the center of the bow. On the feathered end of the arrow passing through the opening D, at least 30 one of the feathers, of which there are usually three, will be caused to traverse the slot 27 so that the side margins of the slot will coat with the opposite sides of the feather to stabilize the arrow 35 against spinning or wobbling in flight.

When the archer desires to employ the sight mirrors F and G, the latter are disposed in their operating position to reflect the target in the mirror F, as before explained.

While I have shown and described a specific 40 embodiment of the invention, I do not limit myself to the exact details of construction and arrangement shown, but may employ such modifications and changes in the parts and their assemblage, as occasion may require, coming within the 45 spirit and scope of the appended claims.

I claim:

1. In an archer's bow, an intermediate bow section having an arrow receiving opening leading therethrough formed with a side wall slot 50 through which an arrow may be laterally passed, and means for closing said slot.

2. In an archer's bow, an intermediate bow section having an arrow receiving opening leading therethrough formed with a side wall slot through 55 which an arrow may be laterally passed, a block for filling said slot, and a resilient support for said block.

3. In an archer's bow, an intermediate bow section having an arrow receiving opening leading 60 therethrough formed with a side wall slot through which an arrow may be laterally passed, a block for filling said slot, a resilient support for said block, and means for detaining said block in engagement with the margins of said slot.

4. In an archer's bow, an intermediate bow section having an arrow receiving opening leading 70 through which an arrow may be laterally passed, a plate spring extending over said slot one end of which is fixed to said section and the other end of which is free and curved outwardly, and a block carried on said spring arranged to extend between the margins of said slot to fill the latter.

5. In an archer's bow, an intermediate bow 75

- section having an arrow receiving opening leading therethrough formed with a side wall slot through which an arrow may be laterally passed, a plate spring extending over said slot one end of which is fixed to said section and the other end of which is free and curved outwardly, a block carried on said spring arranged to extend between the margins of said slot to fill the latter, and means for effecting releasable interlocking connection between said block and the margins of said slot.
6. In an archer's bow, an intermediate bow section having an arrow receiving opening leading therethrough formed with a side wall slot through which an arrow may be laterally passed, and an arrow support extending transversely of said opening having an open ended slot forming a guide passage for the arrow feather.
7. In an archer's bow, an intermediate bow section having an arrow receiving opening leading therethrough formed with a side wall slot through which an arrow may be laterally passed, and an arrow support extending transversely of said opening having an open ended slot forming a guide passage for the arrow feather, the margins of said slot converging toward each other from one end thereof toward the other.
8. In an archer's bow, an intermediate section, end sections connected to said intermediate section for longitudinal and pivotal movement relative thereto, sockets on said intermediate section to receive the inner ends of said end sections.
9. In an archer's bow, an intermediate section, end sections, pivot pins hingedly connecting said end sections to said intermediate section, means affording longitudinal movement of said end sections relative to said intermediate section, and sockets on said intermediate section to receive the inner ends of said end sections.
10. In an archer's bow, an intermediate section, end sections connected to said intermediate section for longitudinal and pivotal movement relative thereto, sockets on said intermediate section to receive the inner ends of said end sections, said intermediate section being formed with an arrow receiving opening leading therethrough between said sockets.
11. In an archer's bow, an intermediate section, flexible bow end members connected to said section, plate springs carried by said intermediate section arranged to yieldably oppose flexing of said bow members, and adjustable slides connected to said springs and engaging said intermediate section for varying the action of said springs in resisting flexing of said bow members.
12. In an archer's bow, an intermediate section, bow end members connected to said intermediate section for longitudinal and pivotal movement relative thereto, sockets on said intermediate section to receive the inner ends of said end members, a string connecting the outer ends of said end members, and means for drawing said string taut to bend said end members when the latter are engaged in said sockets, said means being adapted to slacken said string to permit withdrawal of said members from said sockets.

YNGVE J. NYVALL.
